UNITED STATES PATENT OFFICE.

FRANK W. HOMAN, OF PHILADELPHIA, PENNSYLVANIA.

SHOE.

1,269,281.

Specification of Letters Patent. Patented June 11, 1918.

Application filed March 10, 1917. Serial No. 153,875.

To all whom it may concern:

Be it known that I, FRANK W. HOMAN, a citizen of the United States, residing at Philadelphia, in the county of Philadelphia, 5 State of Pennsylvania, have invented a certain new and useful Improvement in Shoes, of which the following is a specification, reference being had therein to the accompanying drawings:

10 The invention has relation in general to shoes and the like, and more particularly to light shoes or slippers intended for house-wear. Its main object is to provide in convenient and practical manner for the attachment of covered heels to that line of 15 footwear.

The invention finds application in the manufacture of footwear having covered heels that are secured in place against the 20 outer surfaces of the soles, as contradistinguished from spring-heel footwear. It is especially applicable in the manufacture of shoes or slippers of the class having soles covered with gusset-leather or other coverings.

The invention consists, stated in general terms, in a shoe or slipper having a covered heel and with the upper margin of the heel-covering extending upward so as to inclose 25 the edge of the heel-seat of the sole, and characterized by having the said margin located externally of the seam or line of fastening uniting upper and sole together, and fastened around the said edge. In the case 30 of a shoe having a covered sole, the said upper margin is fastened to the sole-covering around the edge of the heel-seat, and preferably, though not necessarily in all cases, by the same seam which also unites 35 the covering and lining of the sole together externally of the inturned seam uniting upper and sole together.

The invention is illustrated in the drawings, in which,

40 Figure 1 is a side elevation of the greater portion of a house-shoe or slipper, with a portion of the heel-covering broken away.

Fig. 2 is an edge view of the greater portion of a covered sole with heel attached in 45 accordance with the invention, in readiness for connection with the upper of a shoe or slipper, a portion of the heel-covering being broken away, and the top-lift not having been attached to the heel.

50 Fig. 3 is a bottom view of the parts that are shown in Fig. 2,

Fig. 4 is a view of the parts shown in Fig. 2, but before the upper margin of the heel-covering has been trimmed away close to the fastening seam as in Fig. 2. 60

Fig. 5 is a view showing a covered heel, looking at the breast-end thereof.

The drawings represent the character of the covered heels in connection with which, ordinarily, the invention is carried into effect. The heel shown in the drawings comprises a body composed of a filling 1 of suitable height, in this instance made up of several lifts, a covering 2 surrounding the edge of the said filling at back, sides, and 70 breast, and a top-lift 3. As shown, the lower marginal portions of the covering lap over upon the face of the said body to which the top-lift is applied. Usually, such portions are fastened to the said face, as by cement. The top margins 3^a, Fig. 1, of those portions of the covering which are applied to the breast of the heel-body are lapped over upon that face of the heel-body which comes next to the sole. Around the back and 80 sides, the upper margin 3^b of the covering extends upwardly above the body 1.

The manner of fastening the upstanding upper margin 3^b of the heel-covering to the edge of the sole, after the seat-face of the 85 covered heel has been applied against the external face of the heel-seat portion of the sole, may vary in practice. In the illustrative embodiment, in which the covered heel is applied to a covered sole, the same seam, 90 4, which unites the margin of the outer covering 5 of the sole 6 with the margin of the sole-lining 7 around the edge of the said sole, serves also to effect the said fastening of the upper margin of the heel-covering 2 to the 95 edge of the sole. In the case of the said embodiment, the covering 5, sole 6, lining 7, and covered heel are assembled together, and are combined together by means of the seam 4, prior to their connection with the 100 upper 8 of the shoe or slipper. In the case of a shoe or slipper of the type of that shown in the drawings, in which the shoe or slipper is turned after the sole with heel attached has been connected with the upper 105 by means of a seam 9 joining together the edge-portions of the sole-covering, sole-lining, and upper, the said seam is inturned in the turned shoe or slipper, and the seam 4 is located externally of such seam 9. 110

What is claimed as the invention is:—

1. A shoe having a covered heel, with the

upper margin of the heel-covering extending upward so as to inclose the edge of the heel-seat of the sole, and with the said margin located externally of the seam uniting upper and sole together, and fastened to the sole around the said edge.

2. A shoe having a covered sole, and also having a covered heel with the upper margin of the heel-covering extending upward so as to inclose the edge of the heel-seat of the sole, and with the said margin located externally of the seam uniting upper and sole together and fastened to the sole-covering around the said edge.

15 3. A shoe having the upper thereof united to the sole by an inturned seam, with said

sole provided with a covering layer and a lining, and also having a covered heel with the upper margin of the heel-covering extending upward so as to inclose the edge of the heel-seat of the sole, and with the said margin fastened to the sole-covering around the said edge by a seam which also unites the sole-covering and lining together externally of the inturned seam uniting upper and sole together.

In testimony whereof I affix my signature in presence of two witnesses.

FRANK W. HOMAN.
